LAW ENFORCEMENT AUTOMOTIVE VEHICLE

William C. House, Claremont, Calif., assignor to Aerojet-General Corporation, El Monte, Calif., a corporation of Ohio

Filed Nov. 21, 1967, Ser. No. 9,483

Term of patent 14 years

(Cl. D14--3)

FIG. 1 is a perspective view of a law enforcement vehicle, showing my new design;

FIG. 2 is another perspective view, but looking toward the rear of the vehicle which shows anti tip braces extended, and wheel protecting armor in use;

FIG. 3 is a front elevation, also showing anti tip braces extended;

FIG. 4 is a side elevation, showing wheel protection armor in an operative position; and

FIG. 5 is a top plan.

What is claimed is:

The ornamental design for a law enforcement automotive vehicle, as shown and described.
